DESIGN FOR A VEHICLE TIRE

William F. Hoelzer, Greensburg, Pa., assignor to
Pennsylvania Rubber Company, Jeannette, Pa.,
a corporation of Pennsylvania

Application April 29, 1947, Serial No. 138,666

Term of patent 14 years

(Cl. D90—20)

To all whom it may concern:

Be it known that I, William F. Hoelzer, a citizen of the United States of America, residing at Greensburg, in the county of Westmoreland and Commonwealth of Pennsylvania, have invented a new, original, and ornamental Design for Vehicle Tire, of which the following is a specification, reference being had to the accompanying drawing, forming part thereof, in which:

Figure 1 is a plan view of a fragmentary portion of a tire showing my new design, the other portions of the tire being of similar design and appearance and being broken away and removed, and the tire outline being indicated partly by broken lines; and

Fig. 2 is a sectional view taken substantially on the line 2—2 of Fig. 1, the tire outline being indicated partly by broken lines.

The characteristic features of my design reside in the portions shown in solid lines.

I claim:

The ornamental design for a vehicle tire, substantially as shown and described.

WILLIAM F. HOELZER.
